Primary Examiner — Ian Simmons*Assistant Examiner* — Dana L Sipos*(74) Attorney, Agent, or Firm* — Morgan, Lewis & Bockius LLP(57) **CLAIM**

The ornamental design for a bottle and cap, as shown and described.

DESCRIPTION

FIG. 1 is a top, front, right side perspective view of a bottle and cap showing my new design;

FIG. 2 is a front elevation view thereof;

FIG. 3 is a rear elevation view thereof;

FIG. 4 is a side elevation view thereof;

FIG. 5 is a top plan view thereof; and,

FIG. 6 is a bottom plan view thereof.

The broken dot-dash line(s) define the bounds of the claim and form no part thereof.
